(57) **CLAIM**

The ornamental design for a set of reconfigurable sofa cushions as shown and described.

DESCRIPTION

FIG. 1 is a front, right and top perspective view of a set of reconfigurable sofa cushions, showing my new design, in a first configuration.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an exploded perspective view of the separate components of the set of reconfigurable sofa cushions.

FIG. 10 is a front, right and top perspective view of the set of reconfigurable sofa cushions, in a second configuration.

FIG. 11 is a front, right and top perspective view of the set of reconfigurable sofa cushions, in a third configuration; and,

FIG. 12 is a front, right and top perspective view of the set of reconfigurable sofa cushions, in a fourth configuration. The broken lines depict portions of the set of reconfigurable sofa cushions that form no part of the claimed design.

1 Claim, 12 Drawing Sheets
